(57) **CLAIM**

The ornamental design for a weight, as shown and described.

DESCRIPTION

FIG. 1 is a perspective view of a weight showing my new design, wherein the broken line showing portions of FIG. 1 are for illustrative purposes only and form no part of the claimed design;

FIG. 2 is a view in front elevation of the weight shown in FIG. 1, the opposite side being a mirror image;

FIG. 3 is a sectional view taken along the line 3—3 of FIG. 2;

FIG. 4 is an edge view common to both the first and a second embodiment of weight of this invention;

FIG. 5 is a view in front elevation of a second embodiment of weight of this invention, the opposite side being a mirror image; and,

FIG. 6 is a diametric sectional view of the weight of FIG. 5. In both embodiments, the weight is encircled by an annular rim or channel of a resilient material of a color different from the body of the weight. In either embodiment, the body of the weight can be solid, as shown in FIG. 3, or it may be a hollow shell to be filled with particles of heavy material, as shown in FIG. 6. The external appearance of the weight will be the same whether solid or hollow.
